ALKYLATION OF HYDROCARBONS

Joe E. Penick, Woodbury, N. J., assignor to Socony-Vacuum Oil Company, Incorporated, a corporation of New York

Application September 28, 1948, Serial No. 51,572

3 Claims. (Cl. 260—683.4)

1

This invention has to do with the alkylation of hydrocarbons and, more particularly, has to do with the alkylation of hydrocarbons in the presence of hydrogen fluoride catalyst.

During the past decade, considerable progress has been made in the field of alkylation, particularly with the development of improved automotive and aviation motor fuels. A leading development in this field is hydrogen fluoride alkylation, wherein paraffins are alkylated with olefins in the presence of hydrogen fluoride. This process generally involves contacting paraffins, such as isobutane, with olefins, such as n-butene, in the presence of hydrogen fluoride, care being taken that a considerable excess of isobutane be used. In the reaction vessel, wherein the materials are contacted, alkylation of paraffin occurs. The reaction mixture of unreacted paraffin, hydrogen fluoride, alkylate and other hydrocarbon products, is taken from the reaction vessel to a settler, wherein separation of two layers occurs. The lower layer is predominantly hydrogen fluoride and the upper layer contains hydrocarbons saturated with hydrogen fluoride. From the settler, the upper layer is taken to an HF stripper wherein hydrogen fluoride is removed overhead and the hydrocarbons are introduced to a central portion of a fractionating column, generally designated a deisobutanizer. Isobutane is removed as an overhead product from the deisobutanizer and alkylate, such as isoctane, is removed from the bottom thereof and is taken to other fractionation means for separation of desired hydrocarbon fractions.

In the conventional hydrogen fluoride alkylation system briefly described above, it has been considered necessary to remove hydrogen fluoride from the hydrocarbon layer taken from the settler. This makes necessary the use of a relatively large HF stripper in order to process the hydrocarbon layer which contains a large amount of isobutane together with alkylate products and other hydrocarbons. A second characterizing feature of the conventional system is the effective separation of isobutane from the hydrocarbon product taken from the HF stripper. It has been considered essential for efficient operation to remove substantially all of the isobutane from the hydrocarbon product and this has been realized by introducing the hydrocarbon product into an intermediate section of the deisobutanizer and returning a large proportion of isobutane to the top of the deisobutanizer as reflux. As will be recognized by

2

those familiar with the art, the conventional process involves a considerable heat load upon the HF stripper in order to separate HF from the entire hydrocarbon product and also involves a large heat input to the deisobutanizer so as to provide an effective separation of isobutane from the hydrocarbon product.

It has now been discovered that the foregoing process can be simplified with an appreciable reduction in heat requirements for the HF stripper and the deisobutanizer. The simplified process of this invention comprises introduction of the hydrocarbon product from the settler directly to an upper section of the deisobutanizer, dispensing with isobutane recycle thereto, and thereafter introducing the overhead from the deisobutanizer to a relatively small HF stripper.

In order to facilitate description of the process contemplated herein, reference is now made to the accompanying drawing, which shows a typical flow diagram of a preferred arrangement for practicing the invention. For convenience in illustrating the invention, the discussion of the process is directed specifically to alkylation of isobutane with butenes in the presence of concentrated HF. It will be understood, of course, that the invention is applicable also to alkylation of other hydrocarbons in the presence of HF.

As shown in the drawing, an isobutane-butene charge in conduit 1 and HF in conduit 2 are combined and introduced into alkylator 4 through inlet 3. Alkylator 4 may be any suitable vessel resistant to corrosion by HF and provided with a mixing device, such as one or more jet-type and/or perforated plate-type inlets, baffles or stirrers, capable of maintaining liquid hydrocarbons and liquid HF in a state of intimate mixture. The relative proportions of HF and hydrocarbons, and the conditions of temperature and pressure in alkylator 4 are discussed hereinbelow.

The liquid reaction mixture in alkylator 4 is taken through conduit 5 to settler 6 wherein it separates into two phases or layers. The lower layer is predominantly HF with a small amount of tar-like material. The HF layer is withdrawn from settler 6 through conduit 7 with the aid of pump 8 to HF regenerator 9. The tar-like material is separated in the regenerator 9 and is withdrawn through line 10. Regenerated HF is taken as an overhead through line 11 and cooler 12 to line 7. Regenerated HF and HF in line 7 are returned to the alkylator 4 through lines 12, 2 and 3.

The upper layer in settler 6 contains alkylation products, excess isobutane and may contain a small amount of propane and other hydrocarbons, and contains a small amount of HF, and is taken through conduit 13 to an upper section of deisobutanizer 14. The deisobutanizer 14 is operated to provide a rough fractionation of isobutane and alkylation products, with the latter being withdrawn from the bottom of the deisobutanizer 14 through conduit 15. It will be noted that the hydrocarbon layer from settler 6 is introduced directly to the deisobutanizer 14 at an upper section thereof and that no recycle material is introduced at the top of the deisobutanizer to provide reflux therein; that is, there is no recycle reflux in the deisobutanizer. The alkylate withdrawn through conduit 15 contains some isobutane and can be concentrated in a fractionator (not shown).

A major proportion of the isobutane, propane and the HF, are taken overhead from the deisobutanizer through conduit 16, in which is located cooler 17, to accumulator 18. The material in accumulator 18 is pumped through line 19 by means of pump 20. A major proportion, generally about 90%, of the material in line 19 is recycled through line 21, with a minor proportion, generally about 10%, being introduced to HF stripper 22. HF and light hydrocarbons are removed as overhead in stripper 22, through line 23, in which is located cooler 24, to settler 25. Two phases separate in settler 25, the upper phase comprising hydrocarbons and the lower phase HF. The upper phase is recycled to HF stripper 22 through line 26 which connects with line 19. The lower phase, HF, is taken through line 27 to recycle line 21. From the bottom of HF stripper 22, a hydrocarbon fraction comprising propane, isobutane and normal butane is removed through line 28. The latter hydrocarbon fraction, for example, may contain about 10 per cent propane, about 70 per cent isobutane and about 20 per cent normal butane.

To demonstrate the advantages of the present process over conventional HF alkylation procedure, the following comparative examples are set forth in Table I. In the conventional procedure, hydrogen fluoride was stripped from the hydrocarbon reaction product prior to introduction of the latter to a deisobutanizer, which was operated under reflux. In the present process, the procedure described above and shown in the drawing was followed. To provide a proper comparative basis, the alkylation conditions used were essentially the same, with the same quantity, 1000 barrels per day, of alkylate of the same quality, 90.5 octane number, being produced. Conditions of operation were: ratio of isobutane to butenes, 7:1; ratio of HF to hydrocarbon charge, 1:1; 87 per cent HF; temperature and pressure of alkylator, 90° F. and 120 pounds per square inch; contact time, 20 minutes.

Table I

	Deisobutanizer Fractionation, Percent C_4 in Overhead	Plates in Deisobutanizer	Heat Requirements for Deisobutanizer (MBTU/D)
Conventional Process	85 85 70	50 80 50	450 400 200
New Process	70	50	200

¹ Expressed in million B. t. u. per day.

From the results shown in Table I, it will be noted that the saving, effected by the new process, in heat input to the "deisobutanizer" is 125 per cent, when the deisobutanizer contains the same number of plates (50). There is a saving of 100 per cent in heat input, even when the number of plates is increased to 80 in the conventional process.

Conventional alkylation conditions of temperature, pressure, time, isoparaffin-olefin ratio and HF-hydrocarbon ratio may be employed advantageously in the process contemplated herein. For example, the alkylation of isobutane with butenes may be carried out at temperatures between about 0° F. and 150° F., preferably between about 40° F. and 140° F., at pressures at least sufficiently high to keep the hydrocarbons and HF in the liquid phase, and with isobutane-butene ratios of between 2:1 to 15:1, preferably between about 6:1 and 10:1. Ratios of isobutane to butenes of at least 2:1 are essential; since lower ratios tend to cause polymerization of the butenes with resultant decrease in yield of the alkylate product and/or excessive reaction between the butenes and the primary alkylate product because of the relatively low ratios of isobutane to alkylate product in the reaction mixture. The HF may be anhydrous or may have a titratable acidity as low as 70 per cent by weight, and is preferably between about 80 to 90 per cent. The ratio of HF to hydrocarbon charge may be varied considerably, but most satisfactory results are obtained with an excess of HF. Generally, ratios of HF to hydrocarbon charge of at least 1:1 are used. Reaction time is advantageously maintained between about 1 minute and 60 minutes.

While the process of this invention is particularly well adapted for the production of C_8 alkylates from isobutane and butenes, for example, the process is also suitable for other alkylation reactions. By way of illustration, C_7 and C_9 alkylates may be prepared from isobutane and mixtures of propylene and butenes; so also, C_9 alkylates may be obtained by alkylation of isobutane with pentenes. In general, then, the process is suitable for alkylation of alkylatable hydrocarbons, particularly low-boiling isoparaffins, with alkylating agents, particularly low-boiling olefins. As a further illustration of the process, cumene may be prepared herein by reaction of benzene with propylene.

I claim:

1. The continuous process for alkylating an alkylatable hydrocarbon with an alkylating agent in the presence of hydrogen fluoride, which comprises: contacting said alkylatable hydrocarbon with said alkylating agent in an alkylator under alkylating conditions to form a reaction mixture containing an alkylate of higher molecular weight than said alkylatable hydrocarbon; passing said reaction mixture to a settler wherein two phases are formed, one phase being essentially hydrogen fluoride and the other phase being a hydrocarbon phase containing a small amount of hydrogen fluoride, unreacted alkylatable hydrocarbon and said alkylate; separating said hydrogen fluoride phase and recycling the same to said alkylator; passing said hydrocarbon phase directly to the top of a fractionator and fractionating said hydrocarbon phase in the absence of reflux; withdrawing from the bottom of said fractionator a fraction containing substantially all of said alkylate and a small quantity of said unreacted alkylatable hydrocarbon;

withdrawing from the top of said fractionator a fraction containing the bulk of said unreacted alkylatable hydrocarbon, a small amount of hydrogen fluoride and a small amount of said alkylate; recycling a major proportion of said last-mentioned fraction to the alkylator; fractionating a minor proportion of said last-mentioned fraction, removing a bottom product and recycling an overhead product of said unreacted alkylatable hydrocarbon and said small amount of hydrogen fluoride.

2. The continuous process for alkylating an isoparaffin with an olefin in the presence of hydrogen fluoride, which comprises: contacting said isoparaffin with said olefin and hydrogen fluoride in an alkylator under alkylating conditions to form a reaction mixture containing isoparaffins of higher molecular weight than said isoparaffin; passing said reaction mixture to a settler wherein two phases are formed, one phase being essentially hydrogen fluoride and the other phase being a hydrocarbon phase containing a small amount of hydrogen fluoride, unreacted isoparaffin and said higher molecular weight isoparaffins; separating said hydrogen fluoride phase and recycling the same to said alkylator; passing said hydrocarbon phase directly to the top of a fractionator and fractionating said hydrocarbon phase in the absence of reflux; withdrawing from the bottom of said fractionator a fraction containing substantially all of said higher molecular weight isoparaffins and a small quantity of said unreacted isoparaffin; withdrawing from the top of said fractionator a fraction containing the bulk of said unreacted isoparaffin, a small amount of hydrogen fluoride and a small amount of said higher molecular weight isoparaffins; recycling a major proportion of said last-mentioned fraction to the alkylator; fractionating a minor proportion of said last-mentioned fraction, removing a bottom product and recycling an overhead product of said unreacted isoparaffin and said small amount of hydrogen fluoride.

3. The continuous process for alkylating isobutane with butenes in the presence of hydrogen fluoride, which comprises: contacting said isobutane with said butenes and hydrogen fluoride in an alkylator under alkylating conditions to form a reaction mixture containing isoparaffins of higher molecular weight than said isobutane; passing said reaction mixture to a settler wherein two phases are formed, one phase being essentially hydrogen fluoride and the other phase being a hydrocarbon phase containing a small amount of hydrogen fluoride, unreacted isobutane and said higher molecular weight isoparaffins; separating said hydrogen fluoride phase and recycling the same to said alkylator; passing said hydrocarbon phase directly to the top of a fractionator and fractionating said hydrocarbon phase in the absence of reflux; withdrawing from the bottom of said fractionator a fraction containing substantially all of said higher molecular weight isoparaffins and a small quantity of said unreacted isobutane; withdrawing from the top of said fractionator a fraction containing the bulk of said unreacted isobutane, a small amount of hydrogen fluoride and a small amount of said higher molecular weight isoparaffins; recycling a major proportion of said last-mentioned fraction to the alkylator; fractionating a minor proportion of said last-mentioned fraction, removing a bottom product and recycling an overhead product of said unreacted isobutane and said small amount of hydrogen fluoride.
